G. A. MINER

MACHINE FOR OPERATING ON SHOES

Filed March 8, 1924

UNITED STATES PATENT OFFICE.

GEORGE A. MINER, OF GLEN ROCK, NEW JERSEY, ASSIGNOR TO UNITED SHOE MACHINERY CORPORATION, OF PATERSON, NEW JERSEY, A CORPORATION OF NEW JERSEY.

MACHINE FOR OPERATING ON SHOES.

Application filed March 8, 1924. Serial No. 697,788.

This invention relates to shoemaking and particularly to channeled soles, in the channels of which are anchored the stitches for fastening the upper. In a turn shoe the upper is sewn to a leather sole having a channel and a channel-flap, while in a considerable proportion of welt shoes all-leather insoles are used, and in such cases the insole is provided with a channel and a channel-flap. Although these two types of shoes and the methods of making them differ from each other in many respects they have this common feature, viz., that the upper is sewn to a channeled sole having a channel-flap. The preservation of this flap, whether it be a part of the wear sole of a turn shoe or a part of the insole of a welt shoe, is the purpose for which the present invention is provided.

It is necessary, after sewing the inseam of a shoe, whether a turn shoe or a welt shoe, to trim surplus material from the between-substance, which, in both cases, includes the projecting portions of the upper and lining, and, in a welt shoe, the lip of the insole, if there is a lip, and sometimes the inner marginal portion of the welt. Good shoemaking does not require trimming off the channel-flap; in fact, it would be preferable to preserve it, but modern methods of manufacture as practised by the machinery now in commercial use result in cutting off the channel-flap incidentally to trimming off surplus portions of the between-substance. The channel-flap, if preserved intact and laid flat in the channel of the finished shoe, would help greatly to maintain evenness of the shoe bottom, but it has been sacrificed in the interest of what has been considered the more expeditious methods of manufacture.

During the manufacture of both of these types of shoes, namely, those in which the soles are made of leather only and provided with channel-flaps, the soles are tempered with moisture prior to the inseam-sewing operation to soften them, and the channel-flaps are thereby rendered so pliant that they remain in any position to which they may be bent. Furthermore, machines for sewing the inseam of a shoe, whether a turn shoe or a welt shoe, include a channel-guide

arranged to turn up the channel-flap. Consequently, if the flap is not raised before it reaches the inseam-sewing stage it is invariably raised by the channel-guide and usually remains raised when it passes from the inseam-sewing machine to the next machine, which is usually a machine for trimming off surplus stock from the elements through which the inseam stitches extend.

As these trimming machines are now constructed it is practically impossible to avoid cutting off the raised channel-flap incidentally to trimming off the surplus materials projecting from the inseam. Nevertheless, in view of the advantages of preserving the channel-flap so that it will remain an integral part of the finished shoe and fill the depression formed by the channel, an object of the present invention is to provide improved means for closing it instead of cutting it off.

A feature of the invention therefore consists in an improved machine comprising means for closing the channel-flap and means for feeding the shoe so that the closing means will act progressively along the length of the flap. I am aware that machines have been heretofore provided for closing the channel-flap on the tread surface of an outsole, but I am not aware that any machine for that purpose has even been provided with means for feeding the shoe. I therefore desire broad protection for the combination of means for closing a channel-flap, and means for feeding the shoe irrespective of the type of sole of which it is a part.

Another object of the invention is to provide for closing the channel-flap without necessitating an additional handling of the shoe for that purpose, and accordingly another feature consists in combining the flap-closing means with means for feeding the shoe and means for performing some other operation on the shoe. As shown, the invention is embodied in an organization comprising means for trimming surplus material from the between-substance of an inseamed shoe, but it would be within the scope of the invention to combine the flap-closing means with means for performing some operation other than that of trimming the inseam, and the claims appended hereto

are to be so construed wherever the context does not specify inseam-trimming means as one of the elements.

Other features of the invention are hereinafter described and claimed and are shown by the drawings.

Referring to the drawings, in which the invention is illustrated as applied to a well-known type of inseam-trimming machine,

10 Fig. 1 is a side elevation of the upper portion of such machine;

15 Fig. 2 is a view similar to Fig. 1, but on a larger scale, of the work-engaging devices of said machine in working relation to an inseamed shoe having a leather insole provided with a channel-flap;

20 Fig. 3 is a view similar to Fig. 2 except that the insole has a shoulder instead of a lip;

25 Fig. 4 is a plan view partly in section of the flap-closing member and a portion of a member for guiding the surplus material of the between-substance to the trimming locality, the plane of the section being indicated by broken line IV of Fig. 2.

Fig. 5 is an elevation of the elements represented in Fig. 4; and

30 Fig. 6 is a sectional view of an inseamed shoe and shows the channel-flap extending up from the insole. This position of the channel-flap is typical of the condition of an inseamed shoe about to undergo an inseam-trimming operation.

35 The machine represented in Fig. 1 is of the same type as the machine shown in Letters Patent No. 1,226,872, granted May 22, 1917, on application of A. Eppler. This machine is provided with a rotary cup-shaped trimming knife having an annular

40 cutting edge 10. Suitable mechanism (not shown) is provided for driving this knife in the direction indicated by an arrow in Fig. 1. The shoe is supported by cooperative rolls 12, 14 arranged to clamp the welt

45 as shown by Figs. 2 and 3. The roll 12 is positively driven to feed the shoe, while the roll 14, which is carried by a lever 16, is pressed toward the roll 12 by the action of a spring (not shown) connected to said

50 lever. The driven roll 12, which is provided with corrugations on its work-engaging face, is driven in the direction of an arrow in Fig. 2 by gearing (not shown) to feed the work toward the trimming knife 10.

55 The trimming knife 10 is arranged to trim the surplus stock from the between-substance of the shoe and its direction of rotation is such that the drag on the work incidental to its cutting motion is sustained by the clamping rolls 12 and 14. A roll 18

60 is arranged to engage the surplus material of the between-substance in advance of the trimming knife to guide said material to the knife and to turn up any portions thereof that are inclined toward the middle of

the sole. This roll is carried by a shaft 20 journaled in a movable arm 22. Suitable mechanism (not shown) is provided for driving the shaft 20. The periphery of the roll 18 is provided with helical ribs which tend to lift and smooth the uneven portions of the surplus material. All the elements thus far described are mounted on the upper portion 24 of the machine frame.

65 The arm 22 is arranged to swing toward and from the feed roll 12 and is pressed toward the latter by a spring 26 but may be retracted manually to facilitate insertion and removal of the work. For this purpose the arm is mounted on a fulcrum member 28 and is rigidly connected to an arm 30. A rod 32 connects the arm 30 with a treadle (not shown) and extends through an ear 34 on the frame. A spring 26 encircles the rod 32 and is under initial compression between the ear 34 and the arm 30 to raise the latter. When the treadle rod 32 is depressed it swings the roll 18 away from the feed roll and, through suitable connections (not shown), it also retracts the presser roll 14 from the feed roll 12 so that a shoe may be readily placed in working position or removed. With the exception of the roll 18 the elements thus far described and their modes of operation are, to all intents and purposes, the same as those shown and described in the aforesaid patent, the roll 18 differing as hereinafter explained.

70 Fig. 2 includes a portion of an inseamed shoe comprising an upper 36, an insole 38 and a welt 40. A portion of the last is indicated at 42 and one of the inseam stitches is indicated at 44. The flange of surplus upper material projecting from the between-substance is indicated at 46. The insole is provided with a channel 48 to receive the stitches, with a channel-flap 50 and with a rib 52 against which the upper is stitched.

75 After the inseam of the shoe has been sewn it is necessary to trim off the surplus between-substance close to the line of stitches. In a welt shoe this is to give the insole a suitable bottom to receive the outsole, while in a turn shoe it is to make the inside of the finished shoe smooth and comfortable. In a welt shoe the elements to be trimmed include the projecting marginal portions of the upper, lining and toe stiffener, and usually the inner marginal portion of the welt. If the insole has a lip such as that indicated at 52 in Fig. 2 this also requires trimming. At this stage in the manufacture of the shoe the channel-flap 50 normally stands up more or less from the insole as shown by Fig. 6, having been raised to that position by the channel-guide of the inseam sewing machine. This condition is typical of the channel-flap in a turn shoe as well as in a welt shoe, and in either case the channel-flap has heretofore been trimmed off in-

cidentally to trimming the surplus material from the between-substance because it has been easier to trim it off than to avoid doing so. Now, however, the present invention 5 provides means for closing the channel-flap while the trimming knife 10 is trimming the surplus material from the between-substance.

The illustrated channel-closing means comprises a finger having a work-engaging portion 54 and a shank portion 56. As 10 shown, this finger is fixed to the member 22 by a set-screw 58. For this purpose a socket is bored in the member 22 for the reception of the shank 56. These elements provide 15 for adjusting the flap-closing finger in lines parallel to the axis of the roll 18, and if the portion 54 is set in contact with the lower end of the roll 18, the latter will brace it against upward pressure of the work. In 20 any case, the portion 54, by its engagement with the sole, constitutes a gage to control the closeness of trimming.

In practice, the channel-closing finger is subjected also to stresses transversely of the 25 axis of the roll 18, which stresses are due to various causes including the feeding movement of the work and the rubbing action resulting therefrom, but the invention provides also for bracing said finger against 30 these stresses so that it will not be bent or turned about the axis of its shank. Accordingly, the lower end of the shaft 20 or of the roll 18, as the case may be, is provided with an extension 60 of relatively small diameter 35 which serves as an abutment to brace the portion 54. Since the shoe is fed in the direction indicated by arrows 62 in Figs. 4 and 5 its tendency to bend or otherwise displace the flap-closing finger is sustained by 40 the extension 60 in such a way as to relieve the shank 56 from torsional and other stresses and to relieve the set screw 58 accordingly. The tip of the portion 54 is beveled (Figs. 2, 3 and 4) to separate the lining 45 from the channel-flap and the bottom surface of the portion 54 is preferably beveled or rounded, as indicated at 64 in Fig. 5, to reduce the drag due to the feeding movement of the work.

50 Provision is also made for bracing the flap-closing finger against displacement transversely of the arrows 62. For this purpose the work-engaging portion 54 is formed with a substantial semi-circular notch 66 to 55 fit the extension 60.

Since the flap-closing finger is carried by the same retractile arm 22 that provides a journal for the roll 18, it necessarily partakes of the movements of the latter toward 60 and from the rolls 12 and 14, and its cooperative relation to the roll 18 is therefore not disturbed by the movement of the arm when a piece of work is inserted or removed.

The machine elements shown in Fig. 3 are 65 the same as those in the other figures, but

the purpose of Fig. 3 is to show that the invention is usable to close the channel-flap of an insole of another type. In Fig. 3 the upper 36, welt 40 and last 42 do not differ essentially from those shown in Fig. 2, but 70 the insole 68, instead of being provided with a lip or rib like that indicated at 52 in Fig. 2, is formed with a shoulder 70 against which the upper is held by the inseam stitches. An insole of this type is commonly provided 75 with a channel 48 and a channel-flap 50. The work-engaging portion 54 of the channel-closer has a sufficient range of contact with the insole to overlap and close the channel-flap irrespective of variations in the 80 distance between the flap and the material to be trimmed.

Having thus described my invention, what I claim as new and desire to secure by Letters Patent of the United States is: 85

1. A machine for operating upon an in-seamed shoe having a sole provided with a channel-flap and a flange of surplus upper material projecting from the between-substance, comprising means arranged to run 90 inside said flange and close the channel-flap, and means for feeding the shoe to cause said closing means to act progressively along the length of the channel-flap.

2. A machine for operating upon an in-seamed shoe having a sole provided with a channel-flap and a flange of surplus upper material projecting from the between-substance, comprising means arranged to run 100 inside said flange and close the channel-flap, means for simultaneously performing another operation on the shoe, and means for feeding the shoe lengthwise of the channel-flap so that said flap-closing means and the means for performing the other said operation will function progressively. 105

3. A machine for operating upon a shoe having a sole provided with a channel-flap, comprising means arranged to close the channel-flap, means for simultaneously trimming an element of the shoe, and means for feeding the shoe lengthwise of the channel-flap so that said flap-closing means and said trimming means will function progressively. 110

4. A machine for operating upon an in-seamed shoe having a sole provided with a channel-flap, comprising means arranged to close the channel-flap, inseam-trimming means, and means for feeding the shoe to cause said flap-closing means and said trimming means to function progressively. 115

5. A machine for operating upon an in-seamed shoe the sole of which is provided with a channel-flap, comprising a power-driven roll arranged to act on the inner side 125 of the surplus between-substance, means arranged to close the channel-flap, and means arranged to trim off the surplus between-substance.

6. A machine for operating upon an in- 130

- seamed shoe the sole of which is provided with a channel-flap, comprising work-feeding means, means arranged to close the channel-flap, and means for trimming surplus material from the between-substance.
7. A machine for operating upon an inseamed shoe the sole of which is provided with a channel-flap, comprising work-supporting means, means arranged to close the channel-flap, and means for trimming surplus material from the between-substance.
8. A machine for operating upon an inseamed shoe the sole of which is provided with a channel-flap, comprising means arranged to press down the channel-flap, means for trimming surplus material from the between-substance, and means for supporting and feeding the shoe.
9. A machine for operating upon an inseamed shoe having a sole provided with a channel-flap, comprising a roll arranged to engage the inner side of the between-substance, and a member arranged in contiguous relation to an end of said roll to close the channel-flap, said roll and said member having cooperative bearing surfaces by which one is utilized to brace the other against working stresses.
10. A machine for operating upon an inseamed shoe having a sole provided with a channel-flap, comprising means arranged to engage the shoe outside the between-substance to guide the shoe, and means arranged to close the channel-flap and to yield away from said guiding means in a direction substantially parallel to the plane of the sole.
11. A machine for operating upon an inseamed shoe having a sole provided with a channel-flap, comprising means arranged to engage the shoe outside the between-substance to guide the shoe, means arranged to close the channel-flap and to yield away from said guiding means in a direction substantially parallel to the plane of the sole, and a roll carried by said spring-stressed means to engage the inner side of the upstanding between-substance.
12. A machine for operating upon an inseamed shoe the sole of which is provided with a channel-flap, comprising a roll the periphery of which is arranged to engage the inner side of the between-substance and one end of which is arranged to confront the sole, said end having an extension of relatively small diameter, and a member supported otherwise than by said roll to close said channel-flap, said member having a notch in which said extension is arranged to brace the member against stresses transversely of the axis of said roll.
13. A machine for operating upon an inseamed shoe the sole of which is provided with a channel-flap, comprising a movable journal member, a roll journaled in said member so that its periphery may engage the inner side of the between-substance, and means affixed to said journal member and arranged to close said channel-flap.
14. A machine for operating upon a shoe having a sole provided with a channel-flap, comprising a member arranged to guide the shoe, and a member arranged to close the channel-flap, said members being supported independently of each other and arranged so that one braces the other against working stresses.
15. In a machine having means for trimming surplus material from an inseamed shoe, the combination of means arranged to close the channel-flap of the sole, and means movable relatively to said channel-closing means to guide the surplus material to said trimming means.
16. In a machine having means for trimming surplus material from a shoe having a sole provided with a channel-flap, the combination of means arranged to close the channel-flap and gage the closeness of trimming, and means arranged to guide the surplus material to said trimming means, said closing means and said guiding means being relatively movable but arranged so that one braces the other.
17. In a machine having means for trimming surplus material from a shoe having a sole provided with a channel-flap, the combination of two relatively movable devices arranged the one to close the channel-flap and the other to guide the surplus material to said trimming means.
18. In a machine having means for trimming surplus material from the between-substance of an inseamed shoe having a sole provided with a channel-flap, the combination of two relatively movable members arranged the one to close the channel-flap and the other to guide the between-substance to said trimming means, said members being also arranged so that one braces the other against working stresses.
- In testimony whereof I have signed my name to this specification.

GEORGE A. MINER.
